WILLIAM LINDEKE, OF COLLEGE POINT, FLUSHING, NEW YORK.

PERMUTATION LOCK.

Application filed July 2, 1924. Serial No. 723,731.

To all whom it may concern:

Be it known that I, WILLIAM LINDEKE, a citizen of the United States, and a resident of College Point, Flushing, borough of 5 Queens, in the county of Queens and State of New York, United States of America, have invented a new and Improved Permutation Lock, of which the following is a full, clear, and exact description.

10 This invention has relation to locks and has particular reference to an improvement in permutation locks.

One of the outstanding objects of the present invention is to provide a permutation lock in which the bolt is retracted from a locked or projected position in successive stages and in which said bolt is projected or moved to a locked position by a single movement or in one stage.

20 As a further object the invention comprehends an improvement in a permutation lock structure in which the use of dials or other visual indicating means are dispensed with whereby the lock may be readily manipulated at night time or in dark places without the necessity of employing a light.

As a still further object the invention contemplates an improved permutation lock which is comparatively simple in its construction, inexpensive to manufacture and produce, and which is highly efficient in its 30 purpose.

With the above recited and other objects in view, the invention resides in the novel 35 construction set forth in the following specification, particularly pointed out in the appended claims and illustrated in the accompanying drawings, it being understood that the right is reserved to embodiments other than those actually illustrated herein to the full extent indicated by the general meaning of the terms in which the 40 claims are expressed.

In the drawings—

45 Figure 1 is a longitudinal sectional view taken approximately on the line indicated at 1—1 in Fig. 2.

Fig. 2 is a transverse sectional view taken approximately on the line indicated at 2—2 50 in Fig. 1.

Fig. 3 is a longitudinal sectional view taken approximately on the line indicated at 3—3 in Fig. 2.

Fig. 4 is a horizontal sectional view taken approximately on the line indicated at 4—4 55 in Fig. 1.

Fig. 5 is a plan view of a substitute leaf member for the bolt carrier element employed for the purpose of changing the 60 combination.

Referring to the drawings by characters of reference, 10 designates a substantially rectangular lock casing which has provided in one of its end walls 11 a bolt opening 12. A bolt carrier 13 is mounted for longitudinal sliding movement in the casing and carries a bolt 14 which is projectable and retractable through the bolt opening 12 upon longitudinal sliding movement of the carrier in opposite directions. The carrier is 70 provided with a rigid or integral leaf 14^a and a removable and interchangeable leaf 15.

The mechanism for operating the carrier element to project or retract the bolt includes an exteriorly disposed knob 16 mounted for rotary movement on the removable side wall 17 of the casing, said knob having as an inwardly projecting extension thereof a tubular shaft 18 arranged transversely in 80 the casing and having longitudinal diametrically disposed slots 19 and 20. The knob 16 is provided with a bore 21 constituting a continuation of the bore of the tubular shaft 18 and a stem 22 extends 85 through the bore 21 and is provided with a reduced threaded portion 23 extending through the shaft 18. At its outer end the stem 22 is provided with a manipulating knob 24 which overlies the outer end of the 90 knob 16 and at its inner end the threaded portion 23 of the stem is provided with a collar 25 which engages the inner end of the shaft 18 to prevent outward axial movement of the stem with respect to the shaft. 95 The outer face of the knob 16 is provided with a recess or socket 26 within which a coiled expansion spring 27 is mounted for normally forcing a ball 28 outwardly against the confronting inner face of the knob 24.

100

The said confronting inner face of the knob 24 is provided with a recess or socket 29 whereby the spring pressed ball and socket function or cooperate to indicate each complete rotation of the knob 24 and stem 22 with respect to the knob 16 and shaft 18. An interiorly threaded sleeve 30 is threadedly engaged by the threaded portion 23 of the stem 22 and said sleeve is provided with oppositely projecting radial arms 31 and 32 extending through the diametrically opposite slots 19 and 20. The inner end portion of the knob 16 which projects into the side wall 17 of the casing has secured thereto a flange or collar 33 and a spring 34 is connected at one end as at 35 to the flange or collar 33 and its opposite end as at 36 to the side wall 17 for normally rotating the knob 16 and shaft 18 in one direction. The movement of the knob and shaft in said direction under the influence of the spring 34 is limited by the engagement of the arm 32 with a stop pin 37 extending transversely through the casing 10. Under this arrangement it will thus be seen that the arms 31 and 32 are connected with the knob and shaft 18 for swinging movement therewith, while said arms and the sleeve 30 are laterally movable in the case and axially movable with respect to the shaft 18 by relative rotation of the knob 24 and stem 22 with respect to the knob 16 and shaft 18. The bottom wall 38 of the lock casing 10 located adjacent the removable leaf 15 of the bolt carrier has attached thereto on its inner face a plate 39 having a transverse keeper slot 40. The leaf 15 is provided with a plurality of transversely and longitudinally spaced slots 41 and 42 and is provided with an upstanding projection 43 which is transversely and longitudinally spaced from the slot 42. A locking dog 44 is pivoted as at 45 within each slot 41 and 42 and the nose 46 of each dog is normally forced downwardly by a leaf spring 47 whereby the nose protrudes into the keeper slot 40 of the face plate 39. Each dog is further provided with an upstanding leg 48. The stationary or integral leaf 14^a of the bolt carrier 13 is provided with a depending lug or projection 49 and is formed adjacent thereto with a slot 50. The inner face of the upper wall 51 of the casing is provided with a face plate 52 having a series of ratchet or rack slots 53. A spring pressed pawl 54 is pivoted to the lug or projection 49 at 55.

In use and operation of the device, assuming the bolt to be in a projected or locked position as illustrated in Fig. 1 and it is desired to move the same to a locked or retracted position within the bolt opening 12, the operator grasps the outer manipulating knob 24 and turns the same the appropriate number of revolutions with respect to the

knob 16 to axially move the sleeve 30 and its arm 31 laterally in the casing until said arm 31 registers or alines with the leg 48 of the dog in the slot 41. When the arm 31 is in registry with the arm 48 of the first dog the manipulating knob 16 is turned in a direction against the action of the spring 34 to engage the arm 31 with the leg 48. The initial movement of the arm 31 will swing the nose 46 of the dog upwardly and out of engagement with the rear edge 56 of the keeper slot and further continued movement of the arm by turning of the knob 16 will effect a rearward movement of the bolt carrier 13 and a retraction of the bolt 14 a predetermined stage, namely, until the nose 46 of the dog in the slot 42 contacts with the rear edge 56 of the keeper slot 40. At the same time it will be observed that the nose of the pawl 54 will have been brought to a position to engage behind the forward edge of the first ratchet or rack slot 53 in the face plate 52 to preclude accidental movement of the bolt carrier in a forward direction to reproject the bolt 14. The operator then again grasps the knob 24 and rotates said knob and the stem 22 the required number of revolutions to axially move the sleeve 30 and arm 31 to a position in registry or alinement with the leg 48 of the dog pivoted in the slot 42. When this position of the arm 31 is obtained, the knob 16 is again grasped and turned against the action of the spring 34 to initially engage the arm 31 with the leg 48 of the dog to disengage its nose from the rear wall 56 of the keeper slot 40. Further continued turning movement of the knob will cause the carrier to be moved rearwardly and the bolt retracted a further stage of its retractive movement. The operator again grasps the knob 24 and rotates the same together with the stem 22 the required number of revolutions to bring the arm 31 into registry or alinement with the projection 43, after which the knob 16 is grasped and turned against the action of the spring 34 to effect the final retractive stage of movement of the bolt 14.

With the bolt in a retracted position and it is desired to project the same through the bolt opening, the operator grasps the knob 24 and turns said knob and the stem 22 to axially move the sleeve 30 laterally in the casing to the position illustrated in Fig. 2, at which point the arm 32 now registers with the pawl 54. By then turning the knob 16 against the action of the spring 34, the arm 32 initially engages the pawl 54 to swing the same to a position to disengage its nose from the rearmost ratchet or rack slot 53 and a continued swinging movement of said arm 32 will, due to the engagement of the pawl with the lug 49, function to move the carrier outwardly and project the bolt 14 through the bolt opening 12.

The arrangement or position of the dogs and their legs 48 and the various lateral spacing of the same will control the number of turns of the knob 24 required to bring 5 the arm 31 into registry or alinement therewith. For this reason the leaf 15 is detachably associated with the carrier 13 whereby interchangeable leaves may be employed to change the combination of the lock. The 10 ball and socket engagement between the knobs 16 and 24 serves to audibly indicate each relative rotation of the knob 24 with respect to the knob 16 and each of said rotations is also perceptible by the sense of feelings 15 ing of the operator.

From the foregoing it will thus be seen that a comparatively simple yet strong, durable and efficient permutation lock has been devised in which an unlimited number 20 of combinations may be employed and in which the said combination may be readily changed by interchanging the removable or detachable leaves 15 of the bolt carrier member.

25 I claim:

1. In a lock which includes a casing and a sliding bolt, a plurality of laterally spaced latches on the bolt normally engaging the casing for successively locking said bolt in 30 a plurality of partially retracted positions against further retraction, and mechanism for actuating the bolt to effect its retraction in successive stages, comprising an arm movable laterally in the casing to position the 35 same in engagement with the latches successively, and means for rocking said arm when in engagement with the latches to initially release the same and subsequently effect a retractive movement of the bolt.

40 2. In a lock which includes a casing, a sliding bolt means carried by said bolt for normally engaging the casing to successively and positively lock the bolt thereto in a plurality of partially retracted positions against 45 further retraction, and manipulating mechanism for singly operating said means for actuating the bolt to effect its retraction in successive stages comprising an arm having movement in two planes at right angles to 50 each other, the movement in one plane positioning the arm successively in engagement with the bolt locking means whereby the movement in the opposite plane releases and retracts the bolt.

55 3. A lock comprising a casing and a movable bolt mounted therein for projection therefrom and for retraction within the casing, and an operating mechanism for reTRACTING the bolt including actuating means 60 for moving the same in a retractive direction in a plurality of successive stages, in combination with means carried by the bolt for locking the same in said successive retracted stages, said locking means being releasable by the 65 operating mechanism which retracts the bolt.

4. A lock comprising a casing and a movable bolt mounted therein for projection therefrom and for retraction within the casing, an operating mechanism for retracting the bolt in successive stages, said mechanism including a bolt carrier member mounted in the casing for sliding movement, an exteriorly disposed operating knob therefor having a shaft extending transversely through the casing, an axially adjustable arm carried by the shaft, means extending through the shaft and disposed exteriorly of the casing for adjusting the arm axially on the shaft and transversely of the casing, transversely and longitudinally spaced elements on the bolt carrier member successively engageable by the arm for retracting the bolt in successive stages, and means carried by certain of said elements for locking the bolt carrier against retraction and operable upon initial engagement of the arm with said elements for releasing the same.

5. A lock comprising a casing and a movable bolt mounted therein for projection therefrom and for retraction within the casing, an operating mechanism for retracting the bolt in successive stages, said mechanism including a bolt carrier member mounted in the casing for sliding movement, an exteriorly disposed operating knob therefor having a shaft extending transversely through the casing, an axially adjustable arm carried by the shaft, means extending through the shaft and disposed exteriorly of the casing for adjusting the arm axially on the shaft and transversely of the casing, transversely and longitudinally spaced elements on the bolt carrier member successively engageable by the arm for retracting the bolt in successive stages, and means carried by certain of said elements for locking the bolt carrier against retraction and operable upon initial engagement of the arm with said elements for releasing the same, the means for adjusting the arm axially and transversely of the casing provided with audible indicating means whereby an operator familiar with the operation of the lock may gage the position of the arm.

6. In a permutation lock comprising a casing having a bolt opening therein, a bolt carrier mounted for movement within the casing, a bolt carried by the bolt carrier for projection and retraction through the bolt opening, means within the casing and means on the bolt carrier for locking the bolt in successively retracted stages against further retraction, and an operating mechanism capable of manipulation from the exterior for successively acting upon the locking means on the bolt carrier to initially release the same and subsequently retract the bolt a predetermined stage of its movement.

7. In a permutation lock comprising a casing having a bolt opening therein, a bolt

- carrier mounted for movement within the casing, a bolt carried by the bolt carrier for projection and retraction through the bolt opening, means within the casing and 5 means on the bolt carrier for locking the bolt in successively retracted stages against further retraction, an operating mechanism capable of manipulation from the exterior for successively acting upon the locking means on the bolt carrier to initially release the same and subsequently retract the bolt a predetermined stage of its movement, and interengageable means on the bolt carrier and within the casing for preventing 10 movement of the bolt carrier in a direction to project the bolt when in a partially retracted position.

8. In a permutation lock comprising a casing having a bolt opening therein, a bolt carrier mounted for sliding movement in the casing, a bolt carried thereby for projection and retraction through the bolt opening, a rotatory tubular shaft extending transversely through the casing and having longitudinally diametrically disposed slots, an exteriorly disposed operating knob at one end of the shaft, a threaded stem extending through said shaft and a manipulating knob on the outer end of the stem, means for indicating each relative rotation of the stem 15 with respect to the shaft, an exteriorly threaded sleeve engaging the threaded stem, a pair of diametrically disposed arms on the sleeve extending through the slots in the shaft for rotatory movement with the shaft and for axial movement with respect thereto upon relative rotation of the stem to the shaft, a stop pin extending transversely through the casing, means for normally rotating the shaft in a direction to engage one 20 of the arms with the stop pin, a plate in the casing having a keeper slot, a plurality of longitudinally and transversely spaced spring pressed dogs pivotally carried by the bolt carrier and normally engaging in the keeper slot, a leg on each dog engageable by one of the sleeve arms when brought into lateral registration therewith by manipulation of the knob of the stem, and operable by rotation of the operating knob and shaft whereby to initially disengage the dog from the keeper and subsequently move the carrier member and bolt throughout one stage 25 of its retraction, and interengageable means on the bolt carrier and within the casing for preventing movement of the bolt carrier in a direction to project the bolt when partially retracted.

9. In a permutation lock comprising a casing having a bolt opening therein, a bolt carrier mounted for sliding movement in the casing, a bolt carried thereby for projection and retraction through the bolt opening, a rotatory tubular shaft extending transversely through the casing and having longitudinally diametrically disposed slots, an exteriorly disposed operating knob at one 30 end of the shaft, a threaded stem extending through said shaft and a manipulating knob on the outer end of the stem, means for indicating each relative rotation of the stem with respect to the shaft, an exteriorly threaded sleeve engaging the threaded stem, a pair of diametrically disposed arms on the sleeve extending through the slots in the shaft for rotatory movement with the shaft and for axial movement with respect thereto upon relative rotation of the stem to the shaft, a stop pin extending transversely through the casing, means for normally rotating the shaft in a direction to engage one 35 of the arms with the stop pin, a plate in the casing having a keeper slot, a plurality of longitudinally and transversely spaced spring pressed dogs pivotally carried by the bolt carrier and normally engaging in the keeper slot, a leg on each dog engageable by one of the sleeve arms when brought into lateral registration therewith by manipulation of the knob of the stem, and operable by rotation of the operating knob and shaft whereby to initially disengage the dog from the keeper and subsequently move the carrier member and bolt throughout one stage 40 of its retraction.

10. In a permutation lock comprising a casing having a bolt opening therein, a bolt carrier mounted for sliding movement in the casing, a bolt carried thereby for projection and retraction through the bolt opening, a rotatory tubular shaft extending transversely through the casing and having longitudinally diametrically disposed slots, an exteriorly disposed operating knob at one 45 end of the shaft, a threaded stem extending through said shaft and a manipulating knob on the outer end of the stem, means for indicating each relative rotation of the stem with respect to the shaft, an exteriorly threaded sleeve engaging the threaded stem, a pair of diametrically disposed arms on the sleeve extending through the slots in the shaft for rotatory movement with the shaft and for axial movement with respect thereto upon relative rotation of the stem to the shaft, a stop pin extending transversely through the casing, means for normally rotating the shaft in a direction to engage one 50 of the arms with the stop pin, a plate in the casing having a keeper slot, a plurality of longitudinally and transversely spaced spring pressed dogs pivotally carried by the bolt carrier and normally engaging in the keeper slot, a leg on each dog engageable by one of the sleeve arms when brought into lateral registration therewith by manipulation of the knob of the stem, and operable by rotation of the operating knob and shaft whereby to initially disengage the dog from the keeper and subsequently move the carrier member and bolt throughout one stage 55 of its retraction.

11. In a permutation lock comprising a casing having a bolt opening therein, a bolt carrier mounted for sliding movement in the casing, a bolt carried thereby for projection and retraction through the bolt opening, a rotatory tubular shaft extending transversely through the casing and having longitudinally diametrically disposed slots, an exteriorly disposed operating knob at one 60 end of the shaft, a threaded stem extending through said shaft and a manipulating knob on the outer end of the stem, means for indicating each relative rotation of the stem with respect to the shaft, an exteriorly threaded sleeve engaging the threaded stem, a pair of diametrically disposed arms on the sleeve extending through the slots in the shaft for rotatory movement with the shaft and for axial movement with respect thereto upon relative rotation of the stem to the shaft, a stop pin extending transversely through the casing, means for normally rotating the shaft in a direction to engage one 65 of the arms with the stop pin, a plate in the casing having a keeper slot, a plurality of longitudinally and transversely spaced spring pressed dogs pivotally carried by the bolt carrier and normally engaging in the keeper slot, a leg on each dog engageable by one of the sleeve arms when brought into lateral registration therewith by manipulation of the knob of the stem, and operable by rotation of the operating knob and shaft whereby to initially disengage the dog and from the keeper and sub-

sequently move the carrier member and bolt throughout one stage of its retraction, and interengageable means on the bolt carrier and within the casing for preventing movement of the bolt carrier in a direction to project the bolt when partially retracted, said means being engageable by the other

arm when the sleeve is laterally moved to its full extent in the opposite direction to release said means upon movement of the operating knob and shaft and to fully project the bolt from the casing in a single operation.

10

WILLIAM LINDEKE.
